CLAIM

The ornamental design for a solar powered simulation surveillance camera lamp, as shown and described.

DESCRIPTION

FIG. 1 is a front perspective view of a solar powered simulation surveillance camera lamp design showing our new design.

FIG. 2 is a front view of a solar powered simulation surveillance camera lamp.

FIG. 3 is a rear view of a solar powered simulation surveillance camera lamp.

FIG. 4 is a left side view of a solar powered simulation surveillance camera lamp.

FIG. 5 is a right side view of a solar powered simulation surveillance camera lamp.

FIG. 6 is a top view of a solar powered simulation surveillance camera lamp.

FIG. 7 is a bottom view of a solar powered simulation surveillance camera lamp; and,

FIG. 8 is a rear, top front perspective view of a solar powered simulation surveillance camera lamp.

Any shading and cross-hatching are not features of the design but are utilized to illustrate the surface contours of the solar powered simulation surveillance camera lamp design in the drawings.

1 Claim, 8 Drawing Sheets
